UNITED STATES PATENT OFFICE.

ROY D. FAGAN, OF TORONTO, ONTARIO, CANADA.

LIQUID PURIFIER.

Application filed July 6, 1926. Serial No. 120,690.

This invention relates to filtering devices particularly adapted for use in the gasoline line of internal combustion engines, and my object is to devise a filtering device which is simple, effective, easily installed or disassembled and which is to a considerable extent self cleaning. I attain my object by means of a construction which may be briefly described as follows. A circular base is provided with concentric seats to which are secured conical strainers, the outer being of wire while the inner is of chamois or similar material and is provided with a supporting device adapted to keep it distended. To the base is detachably secured a casing provided with a sediment chamber underneath the strainers, the outer strainers being provided with an opening over the sediment chamber.

20 The invention is hereinafter more fully described and is illustrated in the accompanying drawings in which

Fig. 1 is a longitudinal section of my purifier;
25 Fig. 2 a cross section of the same; and

Fig. 3 a detail, partly in section, showing a modification of the supporting means for the inner strainer.

1 is a circular base plate provided intermediate its center and its circumference with an annular flange 2, which flange is adapted to support the conical strainers 3 and 4. Preferably the flange is provided with grooves 5 forming seats for the open bases of the conical strainers, the strainers being held therein by spring wires 6 or the like.

40 The outer strainer is preferably formed of wire gauze and hence is self-supporting. The inner strainer 4 is preferably formed of chamois or other material having sufficiently fine pores. This strainer must necessarily be supported in distended position as it is not capable of self-support. For this purpose I provide means engaging the apex of the cone and the base 1. In Fig. 1 I show a support comprising a coned disk 7 fitting in the apex of the strainer and carried by a rod 8 formed on or secured to the base plate 1.

45

50

In Fig. 3 I show a modification comprising

ing a tapered coil spring 9 engaging the base within the flange 2 and also engaging in the apex of the cone. To the base is secured the casing 10 by means of the screws 11. This casing may be of any convenient form and is provided beneath the strainers with the sediment chamber 12 provided with a drainage opening normally closed by the screw plug 13. Above the sediment chamber an opening 14 is preferably formed in the outer strainer through which may pass any sediment fine enough to pass through the outer strainer and which has been caught by the inner strainer. 55 60 65 70

In the outer end of the casing is formed an inlet 15 for connection with a gasoline supply pipe. A similar outlet 16 is formed in the base plate between the flange 2 and the center of the plate. A lug 17 is provided on the casing whereby the device may be secured to a suitable supporting part. 70

It will be noted that the opening 14 in the outer strainer is located adjacent the base of the inner strainer. The liquid passing through the device flows towards the bases of the strainers and thus cleans off any sediment on the inner strainer and carries it towards the opening 14. This arrangement of the opening also tends to prevent any fresh liquid from passing therethrough. 75 80

What I claim is:

1. A purifier comprising a base; an annular flange on the base formed as a strainer seat; an inner conical fibrous strainer having its open base secured on said flange; a support for the inner conical strainer extending from the purifier base to the apex of the cone; an outer strainer of wire also having its open base secured on said flange; and a casing detachably secured to the base and provided with a sediment chamber beneath the strainners, the outer strainer having a drain opening in its under side adjacent the base of the inner conical strainer and over the sediment chamber to permit of the escape of sediment from between the strainners. 85 90 95

2. A purifier comprising a base; an annular flange on the base formed as a strainer seat; an inner conical fibrous strainer having its open base secured on said flange; a support for the inner conical strainer comprising a tapered coil spring engaging the puri- 100

fier base and the inner side of the inner conical fibrous strainer; an outer strainer of wire also having its open base secured on said flange; and a casing detachably secured to the base and provided with a sediment chamber beneath the strainers, the outer strainer having a drain opening in its under side

adjacent the base of the inner conical strainer and over the sediment chamber to permit of the escape of sediment from between the strainers. 10

Signed at Toronto, Canada, this 30th day of June, 1926.

ROY D. FAGAN.
